UNITED STATES PATENT OFFICE.

FLEMING B. FOWLER, OF BALTIMORE, MARYLAND.

VENTILATOR.

Application filed August 31, 1927. Serial No. 216,655

This invention relates to ventilators of the type adapted to be used individually with windows of dwellings, office buildings, etc.

My invention is directed toward facilitating influx of fresh air into buildings under regulatory control without the annoyance and dangers occasioned by direct drafts and without obstructions to the passage of light through the windows.

10 The above desiderata I aim to secure through provision of a ventilator which is very simple in construction; conducive to manufacture at small cost; adaptable to windows regardless of variations in their nominal width; and easily regulatable to govern the extent of ventilation.

Other objects and attendant advantages of this invention will be readily apparent from the following description of the typical 20 embodiment illustrated in the accompanying drawings.

Fig. I is a fragmentary elevation of the inside of a window with my improved ventilator in place, certain parts of the latter 25 being broken away and in section for better disclosure of important details.

Fig. II is a vertical section of the organization, taken as indicated by the arrows II-II in Fig. I.

30 Fig. III is a perspective illustration of the various parts constituting the casing of the ventilator and the relation in which they are assembled.

Fig. IV is a fragmentary perspective view 35 showing the construction of the louver shutters and the way in which they are connected for simultaneous actuation to control ventilation.

Fig. V is a fragmentary perspective view 40 showing how the louver shutters are constructed with integral actuating arms by die stamping from sheet metal in accordance with my invention.

Fig. VI is a detail section—on a magnified 45 scale—of the area bounded by the dot and dash circle VI in Fig. II; and,

Fig. VII is a detail end view of one of the upper corners of the ventilator.

With specific reference, first more particularly to Figs. I and II, 10 comprehensively designates the ventilator which is shown applied to an ordinary window whereof the jambs of its frame are indicated at J, J, the sill at S and the lower sash at N, the latter 55 engaging slideways or grooves G in said jambs in the usual manner. As illustrated to

best advantages in Figs. II and III, the casing of my ventilator comprises counterpart triangular right and left end members 11, 11^a, and a hollow rectangular cover member 12.

The side members 11, 11^a are preferably fashioned from sheet metal with inwardly-directed complementary flanges 13, 13^a along their vertical edges for abutment against angle mounting pieces 14, 14^a adapted to be secured to the jambs J, J of the window frame by means of screws 15, the narrow flanges 16, 16^a of said mounting pieces being perforated as at 17 for passage of the screws. Secured to the mounting pieces 14, 14^a, preferably by spot welding, are forwardly-projecting screw threaded studs 18, 18^a which are suitably allocated for registry with horizontal slots 19, 19^a in the flanges 13, 13^a of the triangular end members 11, 11^a. As shown, nuts 20 are employed with the studs 18, 18^a to clamp the end members 11, 11^a in position after adjustment in a manner later on explained. With reference again to Fig. III it will be noted that the end casing members 11, 11^a are also provided along their sloping edges with inwardly-directed lateral flanges 21, 21^a for retainment of a deflecting baffle 22 (Figs. I and II) which closes the frontal portion of the ventilator. This deflecting baffle 22 may be of any suitable material, although ordinarily I prefer to construct it of glass so that the passage of light through the window is not obstructed. Again, if the curative properties of sunlight are desired, I may employ glass of a kind promoting passage of violet rays.

The hollow rectangular cover member 12 (Figs. I, II and III) is likewise struck from sheet metal to channel cross section with provision of comparatively deep downward perimetric flanges 23 to lap the end casing members 11, 11^a after the manner of a lid, and to rest back and front on the top edges of the mounting pieces 14, 14^a and shoulders 24, 24^a, respectively, at the forward upper corners of said end members. The depending flange 25 surrounding the opening through the cover member 12 is joggled as at 26 (see Fig. VI) to afford a seat for a snugly-fitting removable insect screen 27. This screen embodies two rectangular frames 28, 29—one fitting within the other with just sufficient clearance therebetween to clampingly engage the screen mesh 30. After placement, the mesh 30 is folded around the

outer frame 29 so that the edge margins thereof occupy a perimetric recess 31 provided through offsetting of the metal about said frame. The edges of the wire mesh 30 are thus protected against being torn loose during removal of the screen 27 from the cover member 12.

In order that ventilation through the screen 27 may be controlled at will, I provide means in the form of a louver 32 which is incorporated with the cover member 12. This louver 32 comprises a multiplicity of longitudinally-arranged shutters 33 formed from sheet metal blanks with their upper and lower edges respectively curled about wire reinforcing rods 34, 35 which serve to stiffen them against flexure. As shown in Fig. IV, the rods 34 project somewhat beyond the ends of the louver shutters 33 so as to be engageable in uniformly-spaced and suitably-aligned bearing apertures in the deeper portions 25^x of the internal flanges 25 of the cover member 12. At opposite ends, the louver shutters 33 have actuating arms 36, 36^a which are pivotally co-ordinated by coupling elements 37, 37^a fashioned from bar stock. The forward ends of these coupling elements 37, 37^a are bent perpendicularly outward to serve as manipulating handles, and formed with screw threaded extensions 38, 38^a beyond shoulders 39, 39^a for projection through arcuate slots 40, 40^a in the end casing members 11, 11^a and engagement exteriorly by wing nuts 41, 41^a, see Fig. I. As shown in Fig. III, the slots 40, 40^a are open at the upper horizontal edges of the end casing members 11, 11^a for clearance of the coupling element handles 38, 38^a incidental to application or removal of the cover member 12. In Fig. V I have shown a way in which blanks B for the shutters 33 may be conveniently and economically fashioned with the arms 36, 36^a integral, by stamping from strip sheet metal.

The procedure in assembling and installing the ventilator is as follows:

The mounting pieces 14, 14^a are first secured to the jambs J, J of the window frame, with their lower ends resting on the sill rail R, by means of the screws 15. The end casing members 11, 11^a are next brought up against the mounting pieces 14, 14^a the nuts 20, 20^a applied to the studs 18, 18^a, and the deflecting baffle 22 slipped into place so as to lay at an inclination against the oppositely-directed sloping flanges 21, 21^a of the end casing members 11, 11^a with its bottom edge resting on the sill rail R. The end casing members 11, 11^a are thereupon shifted toward each other until they contact firmly with the contiguous edges of the deflecting baffle 22, and the nuts 20, 20^a turned up tight to subsequently hold said end members securely against accidental displacement.

In this connection it is to be particularly noted that by virtue of the slots 19, 19^a, in the end casing members 11, 11^a, the ventilator is adaptable to windows varying in nominal width without requiring special fitting on the job. Installation is completed by application of the cover member 12 as a unit with the screen 27 and the louver 32 already placed, the projecting handles 37, 37^a of the coupling elements 75 being incidentally slipped into the open-ended arcuate slots 39, 39^a of the end casing members 11, 11^a. In use of the device, the louver shutters 33 are simultaneously shiftable by manipulation of the handles 38, 38^a, and may, thereafter, be secured in any desired position of adjustment, simply by tightening the wing nuts 41, 41^a, whereby the shoulders 39, 39^a of said handles opposing the wing nuts are drawn against the insides of the end members 11, 11^a. Attention is directed to the fact that the spacing of the centers of the louver shutters 33 is somewhat less than the width of the latter. Accordingly when the louver is entirely closed the shutters overlap to form a perfect closure.

In order to prevent entrance of water beneath the lower edge of the deflecting baffle 22, I cover the latter at the designated region with the rubber or the like, as indicated at 42, in Fig. II, to form a seal with the sill rail R of the window frame.

The novel construction of the device obviously renders its disassembling very easy 100 for the purpose of cleaning the component parts as may be required from time to time. The construction is further advantageous in that the screen 27 may be readily removed for renewal of the wire mesh 30 when this becomes necessary.

Having thus described my invention, I claim:

1. A ventilator of the character described comprising a deflecting baffle; counterpart triangular end casing members struck from sheet metal with inwardly-directed complementary flanges along vertical edges for attachment to the window frame as well as similar flanges along inclined edges to overlap and retain the deflecting baffle, and an open screen cover member also struck from sheet material with perimetric flanges to fit over the end casing members and the deflecting baffle.

2. A ventilator of the character described comprising counterpart-triangular end casing members with inwardly directed flanges, a deflecting baffle sustained between the end casing members, angle-section mounting pieces adapted to be secured to the window jambs and having forwardly projecting studs allocated for registry with horizontal slots in the end casing flanges to permit shifting of the latter relative to the mount-

ing pieces in adapting the ventilator to the window, and clamp nuts engaging the studs aforesaid to secure the end casing members after adjustment.

- 5. 3. A ventilator of the character described comprising end casing members, a deflecting baffle sustained between said end casing members, an open cover member struck to channel cross section from sheet
- 10 material with a comparatively-deep downward perimetric flange adapted to engage over the casing members and the deflecting

baffle, a screen snugly fitting a seat formed by inward joggling of the flange around the opening through said cover member, and said screen comprising interfitting frames arranged to clampingly engage the edges of the screen between them with the edge margins occupying a perimetric recess about the outer of said frames.

In testimony whereof I have hereunto signed my name at Baltimore, Md., this 27th day of August, 1927.

FLEMING B. FOWLER.
